CLAIM

The ornamental design for a kitchen implement handle, as shown and described.

DESCRIPTION

FIG. 1 is a front, perspective view of a kitchen implement handle showing a first embodiment of our new design; FIG. 2 is a front view thereof, rear view being a mirror image of the front view;

FIG. 3 is a right side view thereof, the left side view being a mirror image of the right side view;

FIG. 4 is a top view thereof; and

FIG. 5 is a bottom view thereof.

FIG. 6 is a front, perspective view of the kitchen implement handle of FIG. 1 illustrated with additional subject matter in broken lines per one example of use of the kitchen implement handle;

FIG. 7 is a front view thereof, the rear side view being a mirror image of the front view;

FIG. 8 is a rear view thereof;

FIG. 9 is a right side view thereof, the left side view being a mirror image of the right side view;

FIG. 10 is a top view thereof; and

FIG. 11 is a bottom view thereof.

FIG. 12 is a front, perspective view of the kitchen implement handle of FIG. 1 showing embodiment 1 with additional environmental subject showing in broken lines;

FIG. 13 is a front view thereof, rear view being a mirror image of the front view;
FIG. 14 is a right side view thereof, the left side view being a mirror image of the right side view;
FIG. 15 is a top view thereof; and
FIG. 16 is a bottom view thereof.
FIG. 17 is a front, perspective view of the kitchen implement handle of FIG. 1 showing embodiment 1 with additional environmental subject showing in broken lines;
FIG. 18 is a front view thereof, rear view being a mirror image of the front view;
FIG. 19 is a rear view thereof;
FIG. 20 is a right side view thereof, the left side view being a mirror image of the right side view;
FIG. 21 is a top view thereof; and
FIG. 22 is a bottom view thereof.
FIG. 23 is a front, perspective view of a kitchen implement handle showing a second embodiment of our new design;
FIG. 24 is a front view thereof;
FIG. 25 is a rear view thereof;

FIG. 26 is a right side view thereof, the left side view being a mirror image of the right side view;
FIG. 27 is a top view thereof; and
FIG. 28 is a bottom view thereof.

FIG. 29 is a front, perspective view of the kitchen implement handle of FIG. 23 illustrated with additional subject matter in broken lines per one example of use of the kitchen implement handle;

FIG. 30 is a front view thereof;
FIG. 31 is a rear view thereof;

FIG. 32 is a right side view thereof, the left side view being a mirror image of the right side view;

FIG. 33 is a top view thereof; and
FIG. 34 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design.
